UNITED STATES PATENT OFFICE

CLIFFORD W. PETERS, OF HUNTINGTON, WEST VIRGINIA

DOLLY

Application filed November 8, 1929. Serial No. 405,560.

This invention relates to wheeled carriages and more particularly to adjustable wheeled carriages or dollys for supporting objects for easy movement.

The attractive display of goods is an important element of successful merchandising. This is particularly true in the selling of radio sets, furniture and the like and it is among the objects of my invention therefore to provide a carriage on which goods may be easily moved from place to place to facilitate their display; to provide a carriage for the display of goods which is attractive in appearance; to provide a wheeled carriage which will support the goods out of contact with the floor but not lifted so high that their normal appearance is materially changed; to provide a wheeled carriage which may be easily and quickly adjusted to fit different sizes of articles to be displayed.

The above and other objects will appear from the following description, reference being had to the accompanying drawings illustrating a preferred embodiment of my invention and in which similar reference characters designate similar parts throughout the several views.

In the drawings, Fig. 1 is a perspective view of my display carriage; Fig. 2 is a fragmentary side elevation, partly in section and illustrating a leg of a radio set or other piece of furniture in its supported position; and Fig. 3 is a detached view of a double forked yoke member.

A great many types of furniture such as cabinet type radio sets and the like are mounted on legs. These legs are not provided with casters or other means to facilitate movement as, when the article is placed in a home, it ordinarily remains in one position. However, in displaying this type of goods in a salesroom it is frequently necessary to rearrange the display and move the various articles about. To facilitate this I have devised an adjustable carriage or dolly which may readily be moved in any direction and which may be adjusted to support articles having different leg spacings.

My dolly, in the form illustrated, has four leg supporting cups 1, preferably made of

rubber or other resilient material, secured to the outer ends of the pivoted arms 2. These arms 2 may be formed from flat strip metal and are so shaped that the portions 2a, to which the cups 1 are secured, are supported just out of contact with the floor by the caster wheels 3. These wheels 3 may be of the well known swiveled caster type to provide easy movement of the dolly in any direction and are supported by the brackets 4 which are secured to the arms 2 by the screws 5.

The inner ends of the arms 2 are adjustably secured in the yoked members 6 and 7 by means of bolts 8 and nuts 8a which extend through holes 9 in the fork portions of members 6 and 7 and corresponding holes in the inner ends of arm 2. The fork portions of yokes 6 and 7 are spaced to allow the arms 2 to be swung freely about on the bolts 8 when the nuts 8a are loose. When the nuts are tightened the forks are compressed and the arms 2 are held securely in place by friction between the inner surfaces of the yoke forks and the ends of the arms 2.

The yoke member 6 has an integral rigid rod portion 10 extending at right angles to the yoke portion. This rod 10 has a sliding fit in a tubular member 11 which is secured to the short rod portion 12 of the yoke member 7 by the screw 13. A thumb screw 14 has threaded engagement with the wall of the tube 11 and is adapted to butt against the rod 10 locking it in any desired position.

The assembly of the arms 2 and yokes 6 and 7 comprises an adjustable chassis for my improved dolly. The wheels 3 support this chassis out of contact with the floor and allow it to be moved about with minimum effort.

As shown in Fig. 2 wing-nuts 15 may be substituted for the standard hexagonal nuts 8a to facilitate adjustment of the carriage.

From the above description it will be seen that by loosening the thumb screw 14 and sliding the rod 10 into or out of the tube 11, the distance between the supporting cups 1 on the left side of the carriage and those on the right side of the carriage (Fig. 1) may be decreased or increased without disturbing the spacing between the front and

rear cups. To change the spacing between the front and rear cups the nuts 8a or 15 are loosened and the arms 2 moved about the bolts 8 until the cups are the desired distance apart.

The rod and tube construction provides means for adjusting the carriage to support articles of different widths and the pivoted arms allow the carriage to be adjusted to the 10 desired depth. It is also possible to set the cups 1 in position to support articles whose legs are not arranged in rectangular relation.

In addition to supporting the legs of an article in position on the carriage, the rubber 15 cups 1 also serve as bumpers to lessen the shock if the dolly strikes against another object. This shock absorbing effect protects both the dolly and the article supported thereon.

20 My improved dolly may be quickly and easily adjusted to support any size of article whose leg spacings come within the range of adjustment of the dolly used. It may be made in various sizes and designed to support any desired load. It may be easily dismantled for storage or shipment and while I have described and illustrated one embodiment of my invention in some detail, modifications may occur to those skilled in the art 25 30 and I do not, therefore, limit myself to the precise details shown or in any manner other than by the claim appended hereto.

I claim:—

35 A dolly of the class described, the combination of a yoke member having a tubular portion, a second yoke member having a rod portion adapted to telescopically engage said first named yoke, means for adjustably holding said rod portion in said tubular portion 40 to permit variation of the distance between said yoke members, a pair of arms pivoted to each of said yoke members, caster wheels secured to each of said arms, and article supporting means disposed below the plane of 45 said arms comprising rubber cup members, said arms being independently swingable about their pivot points to vary the distance between said cups and means for locking said arms to prevent relative movement thereof.

50 In testimony whereof I hereunto affix my signature this 25th day of October, 1929.

CLIFFORD W. PETERS.
